UNITED STATES PATENT OFFICE

SYDNEY S. BREESE, OF WOODBURY, NEW YORK

HYDROFOIL BOAT

Application filed May 6, 1929, Serial No. 360,876. Renewed April 21, 1931.

This invention relates to boats.

More particularly stated, the invention relates to boats of the submerged hydrofoil type, equipped with hydrofoils and so constructed that under running conditions the boat proper or the hull will be supported on the hydrofoils free of the water.

This type of water craft has been variously designated as a hydrodrome, hydroplane boat, hydrovane, etc., and such a structure is shown in Patent No. 1,410,877 granted March 28, 1922 to Bell, Baldwin and Breese.

The most difficult problem to be solved in the design of a boat of the character specified, resides in the steering or turning of such a boat at the high speeds at which the craft can be driven. Great power and leverage are required, as illustrated for instance by the structure disclosed in Patent No. 1,112,405 to Forlanini.

As a matter of fact, a rudder of the conventional type, even when given excessive area and placed in a position to exert great leverage about the pivotal point of the boat, has been found to be unsatisfactory. Furthermore, such a construction presents a great handicap to the commercial development and adoption of this type of boat.

Consideration of the conditions which must obtain to accomplish sharp and accurately controlled changes in direction at high speed, discloses the reasons for this failure of the conventional form of rudder. In the first place, owing to the height of the center of gravity above the plane of the supporting hydrofoils, any change in direction will be accompanied by a tendency of the boat to tilt or list outwardly and to lose its equilibrium and capsizes. Secondly, such a change in the direction of the boat will result in a tendency of the boat to slip or skid sideways.

An obvious and simple method of preventing the undesirable results or tendencies above mentioned, is to slow down the boat very considerably when a turn is made. This, of course, results in a loss of speed. Another method is to exert some force on the craft that will counteract the tendencies mentioned and will cause the boat to bank or incline in the direction toward which it is

turning. This inclination is exactly as necessary as and is strictly analogous to the banking of an aeroplane when turning.

When a boat is turned at a given speed, the sharper the turn, the greater is the centrifugal force to be overcome. From this it follows that a greater power must be exerted on the craft to overcome the centrifugal force or, in other words, the more the boat must be inclined in the direction of the turn.

This invention has for its salient object to provide a simple and efficient steering and controlling mechanism for a boat of the character specified, so constructed and arranged that side slip, outward listing and overturning will be effectively prevented.

Another object of the invention is to provide simple, practical and efficient steering and control mechanism for a hydrofoil boat, so constructed and arranged that turns may be made at sharp angles while the boat is being operated at high speeds without danger of side slip or capsizing.

Another object of the invention is to provide a hydrofoil boat with propelling and steering mechanism so constructed and arranged that the boat will incline when turning toward the center about which the turn is being made and the inclination will bear a definite ratio to the speed of operation of the boat.

Further objects of the invention will appear from the following specification taken in connection with the drawings, which form a part of this application, and in which

Fig. 1 is an elevational view, somewhat diagrammatic, illustrating a hydrofoil boat with steering mechanism constructed in accordance with the invention;

Fig. 2 is a top plan view of the construction shown in Fig. 1;

Fig. 3 is a rear end elevation of the structure shown in Fig. 1;

Fig. 4 is a top plan view, partly broken away, showing a slightly different form of construction embodying the invention;

Fig. 5 is a side elevation illustrating a further modification of the invention; and

Fig. 6 is an end elevation of the rear end

portion of a boat illustrating a further embodiment of the invention.

The invention briefly described consists of a hydrofoil boat comprising a hull having a plurality of sets of hydrofoils suitably carried thereby and adapted to support the boat when the craft is being propelled at a sufficient rate of speed, and propelling mechanism extending downwardly or disposed below the hydrofoils, and means for swinging the propelling mechanism angularly relative to the longitudinal axis of the boat. When the propeller is so mounted and a turn is to be made, the axis of the propeller is angularly adjusted and the angular thrust of the propeller counteracts the centrifugal force acting to overturn the boat.

Further details of the invention will appear from the following description.

In the form of the invention illustrated in Fig. 1, there is shown a boat 10 which may be of any suitable size and shape. Two sets of hydrofoils, A and B, are secured to the hull of the boat and extend downwardly therefrom. Set A comprises hydrofoil blades 15 of suitable construction, which are secured to braces or struts 16 and 17. Set B of hydrofoils is disposed at the stern of the boat and consists of two sections, C and D, disposed laterally of the body of the boat and each comprising hydrofoil blades 20 carried by curved struts or braces 21. The two sections C and D are connected by a cross rod 22 which is mounted in lugs 23 extending rearwardly from the stern of the boat. It will be understood that other forms of hydrofoil structures may be employed and further details of the structure of the hydrofoil sets is deemed unnecessary since the structure is similar to that illustrated in Patent No. 1,112,405 above referred to.

In addition to the two sets of hydrofoils, a fin 25 is secured to the bottom of the boat and extends downwardly therefrom adjacent the bow.

It will be obvious that when a boat of the type illustrated in Figs. 1 and 2 is operating at high speeds and is supported on the hydrofoils, the center of gravity of the boat will be located a considerable distance above the surface of the water. This condition seriously complicates the turning of the boat and gives rise to the tendencies mentioned at the outset of the specification.

In order to counteract the centrifugal force tending to overturn the boat when it is turned at high speed at a sharp angle, the propelling mechanism is mounted in such a way that the line of thrust of the propeller is altered when the boat is turned, thereby causing the thrust to exert a force outwardly or away from the center about which the boat is turning.

Since the propeller is located below the plane of support of the boat, the thrust which

is angularly directed as the boat is turning tends to throw the center of gravity of the boat in a direction opposite to the thrust or, in a direction toward the center about which the boat is turning. This alteration in the direction of the thrust also causes the boat to pivot or swing about the axis of the vertical fin near the bow of the boat and thus the boat is caused to turn and bank simultaneously and in such a manner that danger of skidding or overturning is eliminated.

In the form of the invention illustrated in Figs. 1, 2 and 3, a motor M is mounted in the boat and has connected thereto a shaft which extends downwardly therefrom in a casing 30. The shaft in the casing 30 is connected at its lower end by bevel gears or in any other suitable manner to a propeller shaft which is disposed at right angles thereto and has mounted at the rear end thereof a propeller 31. The casing 30 is pivotally mounted and is adapted to be turned by tiller ropes connected to tiller 32. Attention is called to the fact that the propeller 31 is located below the vertical center of lift of the hydrofoil blades and thus the propeller will be disposed in the water at all speeds when the boat is supported on the hydrofoils. The vertical center of lift at any given speed may be defined for the purpose of this specification as the point about which the lifting forces exerted by the hydrofoils are in balance.

When a turn is to be made, the casing 30 is swung in one direction or the other by the tiller, thus altering the angle of thrust of the propeller and causing the thrust to exert a force outwardly from the center about which the boat is turned. Furthermore, as above stated, since the force is exerted below the plane of support or below the vertical center of lift, it will tend to throw the center of gravity of the body which is disposed above the plane of support in a direction opposite to the thrust or inwardly toward the center about which the turn is being made. In this manner the boat is caused to turn and bank simultaneously, thus counteracting skidding and preventing the boat from capsizing.

In the form of the invention illustrated in Fig. 4, the construction is similar to that shown in Figs. 1 and 2 but differs therefrom in that the motor M is mounted to turn with the casing 30 which extends downwardly therefrom. In this embodiment a handle 35 is used for turning the motor and propelling mechanism.

Any suitable form of a drive for the propeller may be utilized and in Fig. 5 the motor M is connected by an inclined shaft 40 to a hollow shaft 41 splined thereto. Shaft 41 is connected through a universal joint 42 to the propeller shaft 43. Shaft 43 is carried by a casing 44 which is pivoted at 45 and can be swung at an angle by a handle 46. The

propeller 47 is connected to the rear end of the shaft 43.

In Fig. 6 the motor M drives a shaft 50 which is connected by bevel gears 51 and 52 to a vertical shaft 53 carried by a casing 54.

5 A propeller 55 is mounted on a shaft 56 connected by gears 57 and 58 to the shaft 53. The shaft 56 and gears 57 and 58 are housed in a casing 59 which is connected to the lower 10 end of the casing 54. The casing 54 is rotatably mounted and is provided with a handle 60 by means of which it can be angularly adjusted.

It will be obvious that the angular 15 adjustment of the line of thrust will be obtained by the structures shown in Figs. 4, 5 and 6, in the same manner as was described in connection with the embodiment of the invention shown in Figs. 1 to 3. In all of 20 the forms of the invention, the same results are accomplished, and it will be obvious that a hydrofoil boat, provided with propelling and steering mechanism constructed as described can be turned at a sharp angle when 25 running at high speeds without danger of side slip or overturning.

Although certain specific embodiments of the invention have been particularly shown and described, it will be understood that the 30 invention is capable of modification and that changes in the construction and in the arrangement of the various cooperating parts may be made without departing from the spirit or scope of the invention, as expressed 35 in the following claims.

What I claim is:

1. A hydrofoil boat comprising a hull, a plurality of sets of hydrofoils carried thereby, propelling mechanism extending downwardly below the vertical center of lift of 40 said hydrofoils, and means for swinging said mechanism angularly relative to the longitudinal axis of the boat, whereby the boat may be turned, and banked.

45 2. A hydrofoil boat comprising a hull, a plurality of sets of hydrofoils carried thereby, a propeller disposed lower than the vertical center of lift of hydrofoils, means for driving said propeller, and means for tilting 50 said propeller angularly relative to the longitudinal axis of the boat, whereby the boat may be turned, and banked.

3. A hydrofoil boat comprising a hull, a plurality of sets of hydrofoils carried thereby, a propeller disposed lower than the vertical center of left of hydrofoils, means for driving said propeller, and means for tilting 55 the axis of rotation of said propeller angularly relative to the longitudinal axis of the 60 boat, whereby the boat may be turned, and banked.

4. A hydrofoil boat comprising a hull, a plurality of sets of hydrofoils carried thereby, a propeller disposed lower than the vertical 65 center of lift of hydrofoils, means for

driving said propeller, and means for changing the angle of thrust in a substantially horizontal plane during the propulsion of the boat by the propeller, whereby the boat may be turned, and banked.

5. A hydrofoil boat comprising a hull, a plurality of sets of hydrofoils carried thereby, propelling mechanism extending downwardly below the vertical center of lift of said hydrofoils at maximum speed, and 70 means for changing the angle of thrust of said mechanism in a substantially horizontal plane, whereby the boat may be turned, and banked.
